YARN TENSION DEVICE

James D. Friday, Cherryville, N. C.

Application January 16, 1939, Serial No. 251,224

2 Claims. (Cl. 242—150)

In winding yarn or thread from small bobbins onto larger spools for use in twisters or doublers, the yarn is passed through a tension device including a movable tension member and its support, the support being provided at its free end with a leading-in guide or fork composed of diverging arms. As the yarn passes through the tension device, it not only wears away the top yarn contact surface of the support so as to ultimately cut a deep groove therein, but it also cuts into the crotch of the leading-in guide or fork, thereby causing the yarn to roughen or chafe and rendering the movable tension member inoperative by removing its pressure on the yarn. As a consequence, the tension support has had to be replaced frequently at a considerable expense.

In an effort to overcome this undesirable occurrence, it has been proposed to provide a replaceable stationary member between the movable tension member and the upper surface of its support for protecting the support from wear and to permit the further use of a support having a worn upper yarn contact surface. A device according to this prior proposal is disclosed in U. S. Patent 1,708,514, granted April 9, 1929, to J. O. McKean.

While this prior device was satisfactory to some extent, in that it prevented the cutting of a groove in the upper yarn contact surface of the support, it did not entirely solve the problem, the leading-in guide or fork being still left unprotected so that the yarn would continue to cut into the crotch of the leading-in guide or fork and cause roughening or chafing of the yarn to such an extent as to render the support unfit for further use.

The object of my invention, therefore, is to provide a replaceable stationary member interposed between the movable tension member and its support for not only protecting the upper yarn contact surface of the latter from wear, but having an extension at one end disposed to engage or rest upon the arms of the leading-in guide or fork and having a porcelain or like yarn guiding eye which will keep the yarn out of contact with the crotch of the leading-in guide or fork and effectively resist wear by the yarn as it passes to and under the movable tension member. In this way, the support of the tension device is completely protected against wear on all of its yarn contact surfaces, thereby rendering the support capable of almost indefinite satisfactory operation. Also, by the use of the present member, worn tension devices can be used further even though having worn yarn contacting

surfaces, the replaceable stationary member, aside from the yarn guiding eye, being made of case-hardened steel and nickel plated to provide wearing surfaces which are smooth and which will resist the wearing effect of the yarn to a much greater degree than the material of which the tension support can reasonably be made.

The present invention is illustrated as to a preferred embodiment in the accompanying drawing, in which:

Figure 1 is a top plan view of a yarn tension device equipped with a replaceable member constructed in accordance with the present invention.

Figure 2 is a vertical section on line 2—2 of Figure 1; and

Figure 3 is a perspective view of the replaceable stationary member per se.

Referring in detail to the drawing, my invention is illustrated in connection with a yarn tension device comprising a tension head 5 which forms a support for a pair of gravity-operated weighted tension washers 6 which are loosely mounted on pins projecting upwardly from the usual upper yarn contact surface 7 of the support along which the yarn is drawn beneath the washers 6. The usual yarn guide 8, for preventing the washers from jumping off of their pins, is pivoted to the support at 9. At its free end, the support 5 is provided with the usual leading-in guide or fork 10 which is composed of a pair of diverging arms inclined outwardly and downwardly as shown clearly in Figure 2. The usual tension equalizing bar 11 is provided, over which the yarn passes from the washers 6.

To eliminate wear upon the usual upper yarn contact surface 7 of the support 5 and in the crotch of the leading-in guide or fork 10, by the passage of the yarn thereover and therethrough, respectively, or to render further useful, supports having worn yarn contact surfaces, I provide a replaceable stationary member 12 consisting of a plate of case-hardened steel which is nickel plated. One end of this plate is of narrow elongated form and provided with holes 13 for receiving the projecting pins on which the washers 6 are placed, thereby properly positioning the plate on the support 5 with the narrow elongated end portion of the plate disposed on the upper yarn contact surface 7 of the support and in a stationary position. The other end portion of the plate is enlarged laterally and directed outwardly and downwardly at an angle as at 14 so as to span the space between and rest upon the upper surface of the arm of the leading-in guide 10.

or fork 10. This end portion 14 has an opening centrally between the sides thereof and adjacent the point of juncture of said end portion 14 with the other or narrow elongated end portion thereof, of which opening snugly receives a guiding eye 15 preferably formed of porcelain or other material which presents a smooth surface which is extremely wear-resisting so as to have a long period of usefulness and not readily roughen or 10 chafe the yarn passing therethrough. Along one side, the guiding eye 15 is provided with a longitudinal slot 16 to facilitate threading of the yarn into the same, and this slot communicates with a longitudinal slot 17 in the plate portion 15 14 leading inwardly from the outer end edge of the latter so that the yarn may be readily passed into the slot 17 and through the slot 16 to and within the guiding eye 15. When threaded through the eye 15, the yarn is held out of 20 contact with the crotch of the leading-in guide or fork 10 so that the latter is not subjected to wear in the usual way and the yarn contacts only the interior surface of the eye 15 at the inner or closed side of the latter before passing 25 beneath the washers 6. The yarn is then passed over the narrow elongated end portion of plate 12 between the latter and the washers 6 and finally passes over the equalizing bar 11 in the usual way. Thus, the yarn is not only prevented 30 from contacting the usual upper yarn contact surface 7 of the support 5, but is kept out of contact with the crotch of the leading-in guide or fork 10 and only contacts guiding surfaces of the plate 12 and eye 15 which are of high wear- 35 resisting quality. By threading the yarn into the slots 17 and 16 so as to pass through the eye 15 in operation, there is no danger of the threads becoming positioned beneath the narrow elongated end portion of plate 12. However, additional 40 guard against this happening may be had by providing the usual depending side flange 18 on the narrow elongated end portion of plate 12 as shown in the McKean patent above-mentioned, such flange also aiding in keeping the 45 plate in a more rigid relationship to the support.

In view of the above, it will be seen that I have provided a readily replaceable stationary member for coaction with the usual support and 50 movable tension member of a yarn tensioning device, said replaceable member being such as to effectively resist wear and prevent wearing of the usual yarn contact surfaces of the support due to passage of the yarn thereagainst or there- 55 over. When the replaceable member does ultimately wear to some extent, it can be readily

replaced at a slight expense. Numerous tensioning devices of this character which are now in operation or have been discarded can be successfully used for a considerable length of time by use of the present invention in connection therewith, thereby obviating the necessity of replacing the support. The actual need in devices of this kind is supplied completely and not in a partial manner as previously proposed, thereby affording a full solution to the entire problem 10 presented.

What I claim as new is:

1. In a yarn tension device, a tension washer, a stationary support therefor having an upper yarn contact surface under said washer and provided at one end with a forked leading-in guide having a yarn contact surface at the crotch thereof, and a replaceable non-yielding stationary wearing plate having an end portion located upon said upper yarn contact surface for protecting the same from wear, said wearing plate having its other end portion directed outwardly and downwardly and laterally widened to rest upon the upper surfaces of the arms of said leading-in guide and span the space therebetween, said last-named end of the wearing plate having an opening, and a yarn guiding eye removably disposed in said opening and arranged to guide the yarn out of contact with the said yarn contact surface at the crotch of the leading-in guide. 30

2. In a yarn tension device, a tension washer, a stationary support therefor having an upper yarn contact surface under said washer and provided at one end with a forked leading-in guide having a yarn contact surface at the crotch thereof, and a replaceable non-yielding stationary wearing plate having an end portion located upon said upper yarn contact surface for protecting the same from wear, said wearing plate having its other end portion directed outwardly and downwardly and laterally widened to rest upon the upper surfaces of the arms of said leading-in guide and span the space therebetween, said last-named end of the wearing plate having an opening, and a yarn guiding eye removably disposed in said opening and arranged to guide the yarn out of contact with the said yarn contact surface at the crotch of the leading-in guide. 35

3. In a yarn tension device, a tension washer, a stationary support therefor having an upper yarn contact surface under said washer and provided at one end with a forked leading-in guide having a yarn contact surface at the crotch thereof, and a replaceable non-yielding stationary wearing plate having an end portion located upon said upper yarn contact surface for protecting the same from wear, said wearing plate having its other end portion directed outwardly and downwardly and laterally widened to rest upon the upper surfaces of the arms of said leading-in guide and span the space therebetween, said last-named end of the wearing plate having an opening, and a yarn guiding eye removably disposed in said opening and arranged to guide the yarn out of contact with the said yarn contact surface at the crotch of the leading-in guide, said enlarged end portion of the plate having a longitudinal slot extending inwardly from the outer end edge thereof to the outer side of said eye, and the outer side of said eye being provided with an open longitudinal slot registered with the last-named slot to facilitate threading of the yarn into said eye. 40

4. In a yarn tension device, a tension washer, a stationary support therefor having an upper yarn contact surface under said washer and provided at one end with a forked leading-in guide having a yarn contact surface at the crotch thereof, and a replaceable non-yielding stationary wearing plate having an end portion located upon said upper yarn contact surface for protecting the same from wear, said wearing plate having its other end portion directed outwardly and downwardly and laterally widened to rest upon the upper surfaces of the arms of said leading-in guide and span the space therebetween, said last-named end of the wearing plate having an opening, and a yarn guiding eye removably disposed in said opening and arranged to guide the yarn out of contact with the said yarn contact surface at the crotch of the leading-in guide, said enlarged end portion of the plate having a longitudinal slot extending inwardly from the outer end edge thereof to the outer side of said eye, and the outer side of said eye being provided with an open longitudinal slot registered with the last-named slot to facilitate threading of the yarn into said eye. 45

5. In a yarn tension device, a tension washer, a stationary support therefor having an upper yarn contact surface under said washer and provided at one end with a forked leading-in guide having a yarn contact surface at the crotch thereof, and a replaceable non-yielding stationary wearing plate having an end portion located upon said upper yarn contact surface for protecting the same from wear, said wearing plate having its other end portion directed outwardly and downwardly and laterally widened to rest upon the upper surfaces of the arms of said leading-in guide and span the space therebetween, said last-named end of the wearing plate having an opening, and a yarn guiding eye removably disposed in said opening and arranged to guide the yarn out of contact with the said yarn contact surface at the crotch of the leading-in guide, said enlarged end portion of the plate having a longitudinal slot extending inwardly from the outer end edge thereof to the outer side of said eye, and the outer side of said eye being provided with an open longitudinal slot registered with the last-named slot to facilitate threading of the yarn into said eye. 50
